DESIGN FOR AN AUTOMOBILE HOOD TOP ORNAMENT

Glen A. Johnson, Connersville, Ind.

Application March 17, 1948, Serial No. 145,175

Term of patent 7 years

(Cl. D14—18)

To all whom it may concern:

Be it known that I, Glen A. Johnson, a citizen of the United States, residing at Connersville, in the county of Fayette and State of Indiana, have invented a new, original, and ornamental Design for Automobile Hood Top Ornament, of which the following is a specification, reference being had to the accompanying drawing forming a part thereof.

Fig. 1 is a side elevational view of an automobile hood top ornament, showing my new design;

Fig. 2 is a top plan thereof;

Fig. 3 is a horizontal sectional view thereof, taken substantially on the line 3—3 of Fig. 1 and looking in the direction of the arrows;

Fig. 4 is a front elevational view thereof; and

Fig. 5 is a transverse sectional view thereof taken substantially on the line 5—5 of Fig. 5 and looking in the direction of the arrows.

I claim:

The ornamental design for an automobile hood top ornament, as shown.

GLEN A. JOHNSON.
